UNITED STATES PATENT OFFICE.

WILLIAM F. GROENE, OF CINCINNATI, OHIO, ASSIGNOR TO THE R. K. LE BLOND MACHINE TOOL COMPANY, OF CINCINNATI, OHIO, A CORPORATION OF OHIO.

TAPER ATTACHMENT FOR LATHES.

1,401,534.

Specification of Letters Patent. Patented Dec. 27, 1921.

Application filed July 6, 1920. Serial No. 394,089.

To all whom it may concern:
Be it known that I, WILLIAM F. GROENE, a citizen of the United States, and a resident of Cincinnati, county of Hamilton, and State of Ohio, have invented an Improvement in Taper Attachments for Lathes, of which the following description, in connection with the accompanying drawings, is a specification, like characters on the drawings representing like parts.

This invention relates to taper attachments for lathes whereby the lathe tool may be moved either toward or from the center of the lathe while at the same time it is moved toward an end of the lathe at a speed bearing a predetermined relation to its first mentioned movement.

Taper attachments for lathes are used only when it is desired to perform certain operations, and it is therefore desirable to construct the taper attachment so that the lathe tool may be very easily and quickly placed under the control of the same, and likewise may be easily and quickly released from the taper attachment and the parts restored to their normal operating condition.

Various forms of taper attachment for lathes have been heretofore suggested, two different types being well known. In one of these types the cross feed screw is released from the cross slide during the use of the taper attachment so that the cross slide may be moved relative to its carriage by the taper attachment while the cross feed screw is held from a similar movement. In the other type the cross feed screw remains in operative engagement with the cross slide during the use of the taper attachment, and movement is imparted to both the cross slide and feed screw by the taper attachment. The present invention relates more particularly to taper attachments of the latter type.

In the type of taper attachment last mentioned it is customary to provide a taper guide bar which is held against movement relative to the lathe bed, and upon this bar is mounted a sliding shoe constructed to be slid along the guide bar during the use of the taper attachment by the movement of the carriage along the lathe bed. The sliding shoe usually fits tightly upon the guide bar to prevent play from occurring between these parts and after the bearing surfaces of the guide bar become dry and dirty, due partly to the infrequent use of the taper at-

achment, considerable force is required to slide the shoe along its guide bar.

One important feature of the present invention, therefore, is to provide improved means very simple in construction for imparting the movement of the carriage along its bed to the sliding shoe.

Another important feature of the invention is to provide means for relieving the cross feed screw from all lateral and longitudinal stresses during the use of the taper attachment.

Still another feature of the invention is to so construct the taper mechanism that the cutting tool may be easily and quickly placed under the control of the mechanism and released therefrom.

The accompanying drawings illustrate a good, practical form of the invention, the details of which may be modified within the true scope thereof, as defined by the claims.

In the drawings:

Figure 1 is a vertical transverse sectional view taken through a lathe bed and its carriage;

Fig. 2 is an enlarged plan view of a portion of the lathe bed having the taper attachment secured thereto;

Fig. 3 is a rear elevation of the parts shown in Fig. 2;

Fig. 4 is a fragmentary plan view of the portion of the cross slide to which the feed screw nut is secured;

Fig. 5 is a vertical sectional view taken substantially on the line 5—5 of Fig. 4;

Fig. 6 is an enlarged sectional view taken on the line 6—6 of Fig. 2; and

Fig. 7 is an enlarged sectional view taken on the line 7—7 of Fig. 2.

The lathe bed 10 may be of any usual or preferred construction and upon the same is slidably mounted the usual carriage 11 carrying the cross slide 12 to which is secured the usual tool supporting mechanism 13. The cross slide 12 is provided with the usual cross feed screw 14 the forward end of which is slidably received in the cross feed bush 15 and is secured thereto by a spline or key 16. The cross feed screw 14 has threaded engagement with a nut 17 rigidly secured to the lower face of the cross slide 12 by any suitable means such as a stud 18 and screws 19. To the rear of the lathe bed 10 is secured the bed bracket 20. Upon the upper face 21 of this bracket is mounted the

taper attachment guide bar 22, the same being pivotally secured to the face 21 intermediate its end by a pivot pin 23 and the guide bar 22 may be adjusted about its pivot pin 23 to the desired angle by the set-over-knob 24, after which it may be clamped in place by the bolts 25. Upon the guide bar 22 is slidably mounted a shoe 26 provided with a key 27 for taking up wear.

10 The lathe mechanism so far described is old and well known and need not be described herein in further detail.

15 The means for operatively connecting the shoe 26 to the cross slide 12 in such a manner that the cross feed screw will be relieved from both lateral and longitudinal stresses, will now be described. Adjacent the screw 14 and parallel thereto is mounted a draw bar 28; this bar is sufficiently large in cross 20 section to withstand all strains to which it may be submitted, and one end of this bar in the present instance of the invention is slidably received in an aperture formed through the cross-feed nut 17. The other 25 end of the draw bar 28 is slidably supported in a bearing 29 formed in an outboard bracket 30. The bracket 30 has its ends 31 rigidly secured to the lathe carriage 11 and is supported a slight distance above the shoe 30 26 to clear the same. The portion of this bracket in which the bearing 29 is formed lies to the rear of the guide bar 22, as will be apparent from Fig. 2.

It is desirable that means be provided for 35 securing the draw bar 28 to the sliding shoe 26, and it is also desirable that the feed screw 14 be secured to the draw bar 28 to prevent relative longitudinal movement between the same and feed screw. To this end 40 the draw bar has rigidly secured thereto, intermediate its ends, a bearing block 32. This bearing block, in the present embodiment of the invention, has an aperture formed therethrough through which the draw bar extends, and the block is rigidly secured to the bar by a pin 33. The bearing block 32 has a second aperture formed therethrough in which is rotatably mounted an end 34 of the feed screw, and the feed screw is provided 45 with thrust collars 35 to prevent the same from moving longitudinally within the bearing block. The bearing block is conveniently secured to the sliding shoe 26, when it is desired to use the taper attachment, by a 50 clamping stud or bolt 36 which extends through an aperture in the bearing block and has threaded engagement with the shoe 26. The arrangement just described is such that when the bearing block and shoe are secured together by the bolt 36 any movement 55 of the shoe toward or from the carriage 11 will be imparted to the draw bar 28 and screw 14.

As the carriage 11 is moved along the 60 lathe bed, this movement will be imparted to

the shoe 26 by the bar 28 when the bolt 36 is in place, and since the bar 28 is relatively large and is supported to one side of the shoe 26 by the bearing 29, and, if desired, is supported upon the opposite side of the shoe 70 by the bearing 37, in the carriage, the feed screw 14 is relieved from all lateral strains. In order to relieve the feed screw from longitudinal stresses during the use of the taper attachment, the portion of the draw bar 28 75 which extends within the cross screw nut 17 may be rigidly secured thereto, and to this end the nut 17 has a slot formed therein in which the yoke 38 is slidably mounted. The bar 28 passes through this yoke as best 80 shown in Fig. 5, and when it is desired to clamp the bar 28 to the nut 17 all that is necessary is to tighten up the nut upon the threaded stem 39 of the yoke, and this clamps the bar against a wall of the aperture in the nut 17 in an obvious manner. 85

When it is not desired to use the taper attachment, the bolt 36 is removed to release the shoe 26 from the carriage 11, but when the bolt 36 is removed it is necessary to provide means to prevent the cross screw 14 from moving in a lengthwise direction; to this end the draw bar 28 may be rigidly clamped in the bearing 29 by the bolt 40. This is satisfactorily accomplished in the 90 embodiment of the invention illustrated, by providing the bolt 40 with a sleeve 41 (see Fig. 7) slidably mounted in the bearing 29 and this sleeve has a cut-away portion 42 positioned to be forced into clamping engagement with the draw bar 28 by tightening up the bolt 40. 100

From the foregoing description, when read in connection with the drawings, it will be seen that if it is desired to use the taper attachment, all that is necessary is to adjust the guide bar 22 to the desired angle, release the clamping bolt 40 and insert the bolt 36 to secure the draw bar 28 to the shoe 26, and while the parts are in this position the feed screw 14 may be rotated by the hand wheel 43 to adjust the tool toward the work, after which the cross slide 12 may be clamped to the draw bar by tightening up the nut upon the bolt 39. 105

When it is no longer desired to use the taper attachment, all that is necessary is to remove the bolt 36, loosen the nut upon the bolt 39 and tighten up the bolt 40. 110

Claims—

1. In a taper attachment for lathes, the combination of a lathe carriage having a cross slide mounted thereupon, a feed screw operatively secured to the cross slide, a draw bar mounted adjacent the feed screw and 120 slidably supported by the carriage, a bearing block carried by and rigidly secured to the draw bar, said block having the feed screw rotatably mounted therein the feed screw being held against movement bodily relative 125

to the block, a taper guide bar provided with a sliding shoe, and means for securing said block to said shoe.

2. In a taper attachment for lathes, the combination of a lathe carriage having a cross slide mounted thereupon, a feed screw operatively secured to the cross slide, a draw bar slidably mounted adjacent the feed screw, a connection between the draw bar and feed screw for preventing relative bodily movement of the draw bar and feed screw, a taper guide bar having a sliding shoe, means for securing the draw bar to the shoe to impart movement of the latter to the former, means for clamping the draw bar against movement relative to the cross slide, and means for also clamping the draw bar against movement relative to the lathe carriage.

20 3. In a taper attachment for lathes, the combination of a lathe carriage having a cross slide mounted thereupon, a feed screw operatively secured to the cross slide, a draw bar slidably mounted adjacent the feed screw, a bearing block carried by and rigidly secured to the draw bar, said block having the feed screw rotatably mounted therein in the feed screw being held against movement bodily relative to the block, a support for the outer end of the draw bar, means for clamping the draw bar to said support, a taper guide bar provided with a sliding shoe, and means for pivotally securing said block and shoe together.

35 4. In a taper attachment for lathes, the combination of a lathe carriage having a cross slide mounted thereupon; a feed screw operatively secured to the cross slide, a draw bar adjacent the feed screw and slidably supported by the carriage, a connection between the draw bar and feed screw for preventing relative bodily movement of the draw bar and feed screw, a taper guide bar having a sliding shoe, means for removably securing the draw bar to the shoe to impart movement of the latter to the former, and means for clamping the draw bar against movement relative to the cross slide.

50 5. In a taper attachment for lathes, the combination of a lathe carriage having a cross slide mounted thereupon, a feed screw, a cross feed nut for operatively securing said screw to the cross slide, a draw bar slidably mounted in said cross feed nut and extending rearwardly beyond the cross slide, a bearing slidably supporting the rear end of the draw bar, means for clamping the draw bar within said bearing, a bearing block carried by and rigidly secured to the draw bar,

said block having the feed screw rotatably mounted therein the feed screw being held against movement bodily relative to the block, a taper guide bar provided with a sliding shoe, and means for pivotally securing said block and shoe together.

65 6. In a taper attachment for lathes, the combination of a lathe carriage having a cross slide mounted thereupon, a feed screw, a cross feed nut for operatively securing said screw to the cross slide, a draw bar slidably mounted in said cross feed nut and extending rearwardly, a bearing slidably supporting the rear end of the draw bar, means for clamping the draw bar within said bearing, a bearing block carried by and rigidly secured to the draw bar, said block having the feed screw rotatably mounted therein the feed screw being held against movement bodily relative to the block, a taper guide bar provided with a sliding shoe, and means for removably fastening said draw bar to said shoe.

7. In a taper attachment for lathes, the combination of a lathe carriage having a cross slide mounted thereupon, a feed screw, a cross feed nut for operatively securing said screw to the cross slide, a draw bar slidably mounted adjacent the feed screw and extending rearwardly, a support for the rear end of the draw bar, means for clamping the draw bar against movement relative to the cross slide, a bearing block carried by and rigidly secured to the draw bar, said block having the feed screw rotatably mounted therein, the feed screw being held against movement bodily relative thereto, a taper guide bar provided with a sliding shoe, and means for pivotally fastening said block and shoe together.

8. In a taper attachment for lathes, the combination of a lathe carriage having a cross slide mounted thereupon, a feed screw operatively secured to the cross slide, a taper guide bar provided with a sliding shoe, a draw bar slidably supported by said carriage and adapted to impart the movement of the carriage to said sliding shoe, a bearing block rigidly secured to the draw bar and removably secured to the sliding shoe, means for removably clamping the draw bar to the cross slide to impart the angular movement of the sliding shoe to the cross slide, and means for securing said feed screw to said bearing block to prevent relative bodily movement therebetween.

In testimony whereof, I have signed my name to this specification.

WILLIAM F. GROENE.
